F. FRENCH,
SIGNAL PIPE SUPPORT,
APPLICATION FILED MAR. 9, 1916.

1,261,377.

Patented Apr. 2, 1918.

UNITED STATES PATENT OFFICE.

FREDERICK FRENCH, OF DETROIT, MICHIGAN.

SIGNAL-PIPE SUPPORT.

1,261,377.

Specification of Letters Patent. Patented Apr. 2, 1918.

Application filed March 9, 1916. Serial No. 83,036.

To all whom it may concern:

Be it known that I, FREDERICK FRENCH, a citizen of the United States of America, residing at Detroit, in the county of Wayne 5 and State of Michigan, have invented certain new and useful Improvements in Signal-Pipe Supports, of which the following is a specification, reference being had thereto in the accompanying drawings.

10 Railway signal systems, particularly of the interlocking type as now universally used, especially in large railroad yards, include what is known in the art as pipe carriers for the lead outs of the signals and on 15 account of the large number of signals which may be controlled from a single tower there is necessarily a large installation of pipe carriers and lead outs. It is the present practice to make these lead outs of rigid 20 tubing or pipe and to support the same upon pipe carriers having various kinds of foundation. The lead outs are generally disposed in parallelism and from time to time branch off to signals, consequently the tubing or pipes used as lead outs are of certain 25 lengths and must be connected together to form a lead out of a desired length. In consequence of such installation there are necessarily waste sections or pieces of tubing 30 or pipe, which either become scrap or are used in completing a lead out of desired length.

A multiplicity of lead outs necessitates one or more foundations and it has been the 35 practice to connect these foundations by base plates for the pipe carriers. As the number of foundations depend upon the number of lead outs, there is no specified distance between the foundations and naturally there 40 must be on hand a stock of base plates of various lengths which will permit of the base plates being connected from one foundation to another. The base plates are often in the form of malleable iron plates, channel 45 bars or even wood sills. Owing to various lengths of base plates or sills being required, there is necessarily a large stock of material on hand and as no two signal installations are alike, special specifications are necessary.

50 To utilize scrap or short lengths or lead out pipes as supports for carriers and to provide a standard support for such pipes which will be applicable to any foundation, is the paramount object of my invention. 55 By utilizing the tubing or pipe in conjunction with a standard support, I eliminate a

varied stock of signal material, such as different lengths of base plates or sills, besides retaining the strength and rigidity of lead out pipes in forming practically an indestructible fabricated framework upon which pipe or wire carriers, as well as other signal appurtenances may be mounted.

Other features of my invention will appear as the nature of my invention is better understood, and reference will now be had to the drawings, wherein—

Figure 1 is a front elevation of my improved support for the pipe carriers of signal lead outs;

Fig. 2 is a plan of a support with pipe carriers removed therefrom;

Fig. 3 is an end view of the same, showing hook bolts holding a pipe carrier on a support, and

Fig. 4 is a perspective view of a detached support.

In the drawing, 1 denotes foundation blocks or piers of a conventional form commonly used when installing lead outs of signals, said piers having side walls thereof provided with recesses or sockets 2 for the angle heads or hooks 3 of bolts or tie rods 4 employed for anchoring lead out supports upon a pier. A lead out support in accordance with my invention comprises parallel base bars 5 connected, intermediate the ends thereof by transverse parallel upright cleat members 6 carrying parallel dished or concave rest members 7 for carrier holders or 80 tubular supports 8.

The base bars 5 are comparatively flat and are disposed in close proximity with said bars of a length to protrude beyond the upper end of a pier. The protruding ends 95 of the base bars 5 form slots or bifurcations to receive the upper ends of the bolts or tie rods 4 and with nuts 9, or other hold fast devices on the upper ends of the bolts or tie rods 4, the base bars 5 are anchored relative 100 to a pier. The slot or space between the base bars 5 permits of the base bars being shifted on top of the pier relative to the bolts or tie rods 4, consequently the base bars 5 can be adjusted relative to a pier and have 105 no defined position until anchored by the bolt or tie rods 4.

Transverse cleat members 6 have the lower edges thereof in the same plane as the bottom faces of the base bars 5 and said 110 cleat members coöperate with the base bars in obtaining a bearing upon the pier 1 which

is well distributed upon the top of the pier. The cleat members 6 are farther spaced apart than the base bars and support the rest members 7 in a horizontal plane above the pier 1. The rest members 7 are of less length than the base bars, but are well balanced relative to said bars and the cleat members 6 to afford a substantial rest for the holders or tubular supports 8. These 10 holders or tubular supports are made of lengths or pieces of a pipe ordinarily used as lead outs of a signal, and said holders provide a substantial rest for the base pieces or feet 10 of pipe carriers 11. The pipe carriers are of the ordinary and well known type and are retained in engagement with the holders 8 and the rest members 7 by hook bolts 12 some of which engage under the rest members 7 while others simply engage the holders 8, as best shown in Fig. 1. The hook bolts 12 prevent vertical as well as lateral displacements of the pipe carriers 11 and as said hook bolts are detachable relative to the pipe carriers 11, said pipe carriers 25 can be shifted laterally of the holders 8 and properly assembled for carrying a desired number of pipe lead outs.

When two or more foundations or piers 1 are required for supporting a large number 30 of lead outs, the holders 8 can extend from one pier to another, as shown in Fig. 1, thereby tying the piers or foundations together in such a manner that pipe carriers on the holders 8 will be maintained in proper 35 relation even though some of the foundations or piers should be injured or deteriorate in advance of others.

Besides the holders affording a substantial bearing or support for the pipe carriers 40 11 and tying the foundations or piers together, as just mentioned, said holders, particularly in connection with a single foundation or pier, constitute convenient hand grips for easily setting a previously molded 45 or formed foundation block or pier and for carrying a series of pipe carriers prior to connecting the same to a pier. As the holders can be clamped between the rest members 7 and the base pieces or feet of the pipe 50 carrier 11, it is possible to use the short lengths of pipes for the holders and have the confronting ends of the pipes meet on the rest members 7, for instance, as shown at the left hand end of Fig. 1. This allows 55 scrap ends of pipe to be utilized as holders especially when only one or two pipe carriers are to be mounted upon a pier.

From the foregoing it will be noted that a support, such as illustrated in Fig. 4, is 60 applicable to the top of a pier, irrespective of the length of the holders 8 to be supported thereby, consequently the support shown in Fig. 4 becomes a standard article and eliminates plates and sills of various sizes 65 as heretofore used. When installing a sig-

nal system the pipes for the mechanically interlocking lead outs are on hand to be cut and fitted together and it is only necessary to use lengths or scrap ends of these pipes as holders for the pipe carriers. By reducing the stock heretofore maintained for the installation and repair of signal systems there is not only a monetary saving, but the annoyance of handling and maintaining a record of a varied stock is obviated, and the essential elements for signal lead outs reduced to a minimum. 70 75

While in the drawings there is illustrated a preferred embodiment of my invention, it is to be understood that the structural elements are susceptible to such change in size, shape and manner of assemblage, as fall within the scope of the appended claims. 80

What I claim is:—

1. An element of signal installation comprising a pipe carrier, and supporting means therefor including pipes extending transversely of the pipes carried by said pipe carrier and to which pipes said carrier is detachably and adjustably secured. 85 90

2. An element of signal installation comprising base bars, cleat members extending transversely thereof, and rest members on said cleat members adapted as supports for pipe carriers. 95

3. Means for supporting pipe carriers comprising a support, rest members carried thereby, and holders on said rest members adapted for supporting pipe carriers. 100

4. A pipe carrier support including supports, holders on said supports, pipe carriers on said holders, and hook bolts at the ends of said pipe carriers engaging under said holders. 105

5. A pipe carrier support including piers, parallel base bars on said piers and having the ends thereof protruding from the sides of said piers, means engaging in sides of the piers and extending between ends of the parallel base bars to hold said base bars on said piers, rest members supported above said piers by said base bars, holders extending from the rest members of one pier to the rest members of another and pipe carriers clamped to said rest members and said holders. 110 115

6. A pipe carrier support including piers, tie rods at each pier, base bars held on each pier by said tie rods, rest members supported above said piers by said base bars, holders extending from the rest members of one pier to the rest members of another pier, and pipe carriers clamped on said holders. 120

7. A pipe carrier support including piers, pier connecting holders for pipe carriers, 125 cleat members on said piers, and rest members on said cleat members disposed at an angle thereto and supporting said holders superposed relative to said piers.

8. A pipe carrier support including piers, 130

individual base bars on said piers, rest members supported by said base bars, holders common to all of said rest members, pipe carriers, and means for simultaneously clamping said pipe carriers and holders to said rest members.

9. An element of signal installation comprising a pipe carrier, pipes on which the carrier is seated and of the same character as the pipes on said carrier, and supporting means including seats for the pipes and means for securing the carrier to the pipes and the pipes to their seats.

10. Pipe supports for signals, comprising carriers, pipes supporting said carriers, and a support for said pipes connected to said carriers and said pipes.

11. Pipe supports for signals, comprising piers, pipes connecting said piers, carriers extending transversely of said pipes, and means connecting said carriers to said pipes.

12. Pipe supports for signals, comprising

piers, pipes connecting said piers, and pipe carriers clamped on said pier connecting pipes.

25

13. An element of signal installation, comprising a pipe carrier, pipes end to end, a seat for adjacent ends of said pipes, and means for securing said carrier to said pipes and said pipes on said seat.

30

14. An element of signal installation comprising a pipe carrier, a foundation therefor, and a pipe fixed relative to said pipe carrier and said foundation and protruding from the sides of said foundation to facilitate bodily moving said pipe carrier and the foundation thereof.

35

In testimony whereof I affix my signature in presence of two witnesses.

FREDERICK FRENCH.
